STENCILING MACHINE

John C. Smith, Beaver, Pa., assignor to Solar Laboratories, Beaver, Pa., a corporation of Pennsylvania

Application June 21, 1937, Serial No. 149,393

14 Claims. (Cl. 101—123)

This invention relates to stenciling apparatus, and is particularly directed to apparatus for applying any sort of decoration or lettering to articles of glass and other ceramic ware. This type of apparatus is designed to apply ceramic colors to the ware. After application to the ware the coloring materials are fired on the article. The invention may be employed in the lettering and decoration of other articles by the stenciling method and by the use of materials other than ceramic colors, if desired.

More particularly, this invention is directed to a stenciling apparatus which is operative for decorating the internal surfaces of ceramic ware, such as glasses, cups, pitchers, vases, urns or any other vessels of generally cylindrical shape. In the application of the paint, or whatever printing or decorating material is used, to the internal surfaces of the ware, a number of problems arise. It has been the object of the present invention to provide an apparatus which overcomes these problems and enables uniform and rapid decoration of interior surfaces.

In the accomplishment of this object and as the result of the conception herein disclosed, the apparatus of this invention has the following advantages: first, it is possible to interchange the work holding chucks to support any size or shape of hollow ware which it is desired to decorate; second, it is possible to vary spacing of the chuck support and the stenciling unit support so as to provide for appropriate clearance for insertion and withdrawal of the stenciling device with respect to the work; third, the supports for the stenciling unit and the chuck are not only adjustable to different horizontal planes but are pivotally adjustable so as to enable the operator to axially align the stenciling unit and the chuck or the axis of the work, making it possible to accurately place an arcuate stenciling screen with respect to the cylindrical inner surface of the work; fourth, provision is made for moving the squeegee to an operative position on the screen when disposed within the hollow ware, movement of the squeegee to operative position and then operation of the squeegee to the screen being accomplished from a conveniently located knob at the outer end of the stenciling unit; fifth, it is arranged that the operator can move the stenciling head into the interior of the ware, holding the same rigidly in that position with one hand, while manipulating the squeegee with the other; sixth, adjustment is provided for varying the insertive movement of the stencil head and fixing the limits of this movement so that a set of simi-

lar articles may be decorated uniformly and identically; seventh, an improved arrangement of the squeegee and the screen is provided for imprinting a clear and sharp design on the article; and, eighth, adjustment is provided for enabling the operator to control the limits of swing of the squeegee.

Other objects and certain advantages will be more fully apparent from a description of the accompanying drawings in which:

Figure 1 is a side elevation of stenciling apparatus embodying the present invention, and showing the stenciling unit withdrawn from the work preparatory to a stenciling operation.

Figure 2 is a top plan view of the apparatus of Figure 1.

Figure 3 is an end elevation of the machine.

Figure 4 is a fragmentary side elevation showing some parts in cross section and illustrating the first step in the operation of the machine, the stenciling head being shown entering the article to be stenciled.

Figure 5 is a view similar to Figure 4, showing the squeegee or applicator in contact with the stencil during the stenciling operation.

Figure 6 is an enlarged sectional view taken on line 6—6, of Figure 2 but showing the apparatus in the same position as Figure 5.

Figure 7 is a sectional view taken on line 7—7, Figure 6.

Figure 8 is a sectional view taken on line 8—8 of Figure 6.

Figure 9 is a sectional view taken on line 9—9, Figure 6.

Described in general, the apparatus comprises a supporting structure or base, including standards, a chuck unit mounted on one standard, and a stenciling unit mounted on the other standard. The chuck and stenciling units are adjustable for alignment of the article and stencil, and for manipulation of the squeegee relative to the stencil.

The base is indicated at 10 and consists of a bar or body portion having a pair of laterally spaced legs 11 at each end. The two standards 12 and 13 are mounted in slide blocks 14 and 15, each block being formed to slidably engage an upper longitudinal dovetail portion 16 of the rail 17 of the base 10. Each standard is in this manner adjustably secured to the base rail for permitting longitudinal shifting of the two standards in order to accommodate various sizes of work. Each slide block is secured in adjusted position by means of a bolt 18 traversing the slot 19 formed centrally along the rail.

The standard or column 12 supports the stenciling unit 20 on a pivot bearing. The pivot bearing consists of a bracket 21 secured at the top of the support standard. A sleeve 22 is mounted on the bracket by means of a pivot bolt 23 which is screw-threaded into an ear 24 of the bracket 21 and traverses an ear 25 formed integrally with the sleeve 22. The screw projects through both ears and is locked in place by a nut 23a. This arrangement permits the pivot bolt to be adjusted for varying the frictional fit at the pivotal connection whereby the stenciling apparatus will remain in any set position against displacement during stenciling and, at the same time, will be pivotally adjustable without too great effort.

The sleeve 22 slidably journals a tube 26 which forms the main operating arm of the machine. The tube carries an operating knob 27 and a stenciling head 28 at the opposite ends thereof. This tube is journaled in the pivotal support bearing medially of the tube length and is adapted to be rocked in an arc about the axis of the pivot bearing. In addition, the support sleeve 22 permits longitudinal shifting of the tubular shaft or arm. By shifting the assembly axially in the sleeve 22 the operator may properly insert the stenciling head into the work, such as a cup, for the stenciling operation.

30 The stenciling head 28 carries a stencil screen 29 and a squeegee or applicator 30 mounted in operating relation to each other. The stencil consists of a sheet or membrane having design areas, as at 31, through which the paint or ceramic coloring matter may pass. Since this membrane is of fine mesh silk, the stencil is commonly known as a silk screen stencil. The squeegee operates to force coloring matter through the design on the stencil by a wiping action, the co'oring matter being deposited on the surface to be decorated. The membrane is stretched on a frame 32 which is carried on an arm 33 extending from the circular head 34. The arm is fastened to the head by screws 35, and the stencil frame is attached to the arm by screws 36 for convenient removal or replacement.

50 The stencil frame 32 is shaped to conform with the inner surface of the object to be stenciled, and, as illustrated in the drawings, is arcuate to correspond with the cylindrical interior of a tea cup, which is selected as an example to illustrate the general class of work to which the machine is adapted.

55 The chuck unit 37 which supports the work consists of a scoop-like receptacle 38, fashioned of sheet metal in the form of a half cylinder and open at one end to permit entry of the stencil and squeegee assembly. The diameter 60 of the cylindrical section is the same as the outside diameter of the cylindrical article to be decorated. A lip or flange 39 is provided at the open end of the receptacle and projects angularly of the edge a sufficient distance inwardly to 65 engage the edge of the work against displacement. It will be noted that the lip does not extend beyond the inner surface of the work, as this would interfere with proper operation of the stencil. There is, however, sufficient purchase to confine the work firmly in the chuck.

70 Since the article being stenciled must be firmly supported and held in a fixed position during the stenciling operation, provision is made to ensure proper alignment in the receptacle. For this purpose, an abutment pad or disc 40 is secured

at the closed end of the receptacle to engage the bottom of the article and thus provide a positive engagement of the article against the lip at the open end. The work receiving receptacle is secured to a stub shaft 41 projecting from the bore of a pivoted support bracket 42 and held therein by means of a set-screw 43. The stub shaft is provided with a head 44 to which the end wall 45 of the receptacle is secured. Fastening is effected by the screws 46 which pass through the head and the end wall of the receptacle and engage in the abutment plate, thus fastening the three parts rigidly together.

The support bracket 42 for the chuck unit is fixed at the top of the column or standard 13 as previously mentioned. The bracket is of two-piece construction, consisting of the sleeve bracket 42 in which the chuck unit is secured and a collar fitting 42a secured at the top of the column or standard. The two parts are fastened together by a bolt 47 traversing a pair of ears 47a and 47b, each ear respectively being a part of the collar 42a and the sleeve 42. The bolt is in screw-threaded engagement in the ear 47b and functions to draw the two parts tightly together to frictionally hold the sleeve bracket in any selected angular position and yet permit the chuck to be adjusted angularly in order to secure proper alignment of the work surface relative to the stencil.

30 As previously described, the main operating arm 26 of the stenciling unit is pivoted on its support standard. In setting up the machine for decorating a given style of ware, the chuck is adjusted angularly on the support bracket so 35 as to dispose the inner surface of the work in alignment with the stencil when the stencil is in place on the surface of the work. In other words, the chuck axis may be aligned with the axes of the hollow ware.

40 The mechanism of this invention is directed primarily to the decorating of the internal surfaces of articles of glass, metal, or ceramic materials; such as, cups, pitchers, vases, glasses, urns, and other vessels of general cylindrical 45 design. The chuck may be of any convenient size or shape to accommodate the article to be decorated. The nature of the work is such that various arrangements of the chuck to suit the article to be stenciled may be provided. The 50 chuck, as previously described, is readily removable from the support bracket to permit convenient interchange. In the decorating of tea cups, the receptacle illustrated in the drawings is utilized and variations as to length 55 are accommodated for by the installation of abutment plates of proper thicknesses to fit the cup snugly in the receptacle-like chuck against the flange or lip at the open end.

60 In a stenciling operation of this nature, one of the problems arising is that of locating and holding the stencil within the periphery of the article at the proper location with respect to the edge of the article. It is of utmost importance that the stencil be held motionless while 65 the squeegee is operated, otherwise the insignia or design will be smudged or blurred. Moreover, since the machine is intended for use in decorating articles, such as sets of dinner ware, on a quantity production basis, uniformity in 70 the quality and location of the design or insignia is important.

75 The above mentioned difficulties are overcome in the present device by the arrangement of the shiftable stenciling head and pivoted arm. In

operating the machine the stenciling head is shifted longitudinally as a unit to dispose the stencil in the interior of the vessel to be decorated, as shown in the drawings Figures 1 and 4. 5 As will be noted in Figure 4, the arm or tube is shifted a sufficient distance to bring a stop collar 48 into abutment against the sleeve 22. The collar is adjustably fixed on the arm 26 by a set-screw 49 to permit adjustment for various 10 lengths of articles. When the stop is fixed, movement into the duplicate articles to be decorated will always be the same and uniform spacing of the design for the cup edge is assured.

The radial position of the stencil in relation 15 to the work is unchangeable due to the prevention of any rotative movement of the arm or head. The arm is held against rotation by a spider-like arrangement consisting of a perpendicular rod 50, confined between a pair of rods 51 and 52 projecting horizontally from the standard or column, (see Figure 1). The perpendicular rod projects from a collar 53 on the arm which is locked in place by a set-screw 54. The horizontal rods are screw-threaded into a block 55 20 which is secured on the column by a set screw 56. The stenciling unit is thus free to be rocked up or down for alignment with the work and to be moved in or out longitudinally for entry or withdrawal of the stencil with respect to the interior 25 of the work.

The head 28 of the stenciling unit is secured 30 on the operating end of the arm 26 between a collar 57 and a nut 58, screw-threaded on the end of the arm. The head carries a circular track 59 on its inner face for cooperation with a roller 59a in connection with the squeegee operating mechanism. The squeegee 30 is mounted and actuated by means of a bell crank lever 60. The squeegee is pivotally secured on the outer end 40 of one of the arms 61 of the bell crank lever while its opposite arm carries the roller 59a which cooperates with the track 59. The bell crank lever is pivoted at its fulcrum in a block 62, slotted as at 63 to receive the lever, the block 45 being secured on the end of a shaft 64. The shaft 64 is carried internally of the tubular operating arm 26 and is adapted for lateral and rotative movement for actuating the squeegee.

The opposite end of the shaft 64 projects 50 slightly beyond the end of the tubular arm 26 of the stenciling unit, and carries the manipulating knob 27 for operating the squeegee. The knob is fastened to the shaft by means of a set screw 66 and carries a stop pin 67 projecting 55 parallel with the shaft between a pair of limit pins 68 and 68a for limiting the rotative movement of the knob.

The limit pins consist of stub screws, each 60 screw-threaded into collars 69 and 70. The collars are secured on the end of the tubular arm and are locked in place by the stub screws, which project through the collar against the tubular arm. The purpose of this arrangement is to limit the scraping stroke of the squeegee across 65 the stencil. As shown in Figure 9, the two screws 68 and 68a project radially from the arm, and the stop pin 67 operates in an arc between the two, limit screws. This arrangement permits 70 convenient adjustment as to the length of stroke of the squeegee.

As shown in Figures 1 and 4, the squeegee or applicator is normally poised above the surface of the stencil. The bell crank lever assumes a canted position under the influence of a flat spring 71 which is fastened to the bifurcated

block 62 by means of a screw as at 72. The canting of the bell crank lever under spring tension is limited by the roller 59a, which is located at the upper end of the perpendicular arm in a slot 73, and journaled on a screw as at 74. This 5 roller 59 provides a rolling contact with the track 59 as the squeegee is swung across the stencil.

It will be noted from this arrangement, as 10 shown in Figures 1 and 4, that the squeegee and stencil assembly provides a compact unit for convenient entry into the interior of the article to be decorated. The arrangement is such that any 15 difficulty as to access to the interior of the article is obviated; for the squeegee is actuated, both as to pressure and wiping action, by the manipulating knob at the outer end of the operating arm.

The squeegee is mounted on the horizontal arm of the bell crank lever by means of a wing nut 75 traversing a slot 76, to provide adjustment 20 as to location with respect to the stencil. The supporting members for the squeegee consist of a pair of parallel rectangular plates 77 and 78, projecting downwardly at right angles to the arm. In order to secure perfect contact with the 25 stencil, a squeegee block 79 is pivoted between the above-mentioned carrier plates on a pivot pin 80. The wedge-shaped rubber squeegee blade 81 is secured in a slot at the lower side of this block. 30

Referring to Figures 5, 6, and 8, the actuation 35 of the squeegee by means of the manipulating knob is clearly illustrated. In operating the device, the operator grasps the main operating arm 26 with one hand in order to keep the abutment 35 collar 48 against the sleeve 22, and rocks the arm slightly on the pivot bracket 21 in order to bring the stencil frame into contact with the work surface. The manipulating knob is now drawn rearwardly and this rearward motion is transmitted to the operating shaft and to the bifurcated block 62. The bell crank lever 60, being pivoted in this block, is moved bodily rearwardly. The upper end of the perpendicular arm of the bell crank lever is restrained against rearward 40 motion by contact of the roller 59a with the track 59. The result of the rearward movement 45 of the bell crank at its fulcrum point tips the bell crank lever downwardly against the tension of the spring 71, and thus into contact with the 50 stencil.

The stencil frame is spaced slightly away from the work surface because of the thickness of the supporting arm 33 disposed between the stencil frame and the work surface. Downward pressure on the stencil membrane by the wiping edge 55 of the squeegee deflects the membrane so that there is contact of the membrane with the work surface only along the line of the squeegee as shown in Figure 8. This condition assures that 60 the stencil is presented to the work surface in a line contact as the squeegee traverses the stencil in its wiping path. The deflection of the stencil from its normal plane along this line provides 65 clearance on both sides of the contacting portion, permitting the stencil to move in and out of contact with the work in a direct line. As there is no circumferential movement of the stencil, the stencil merely moves down and contacts the work surface under the influence of the squeegee, 70 thereafter moving away when released in a direct line, due to the resiliency of the stencil material, and resulting in a clear-cut print.

The stencil membrane is made of silk and the process is what is generally known as the silk 75

screen method. It is particularly adapted to the decoration of plane surfaces and surfaces which are generally regular in their configuration. The membrane has design areas of a series or plurality of related perforations defined by a coating which renders the non-designed areas impervious to the coloring matter. The coloring matter may be ink, paint, or other suitable material, and is applied to the surface of the membrane so as to be forced through the perforations of the design areas by the action of the wedge-shaped wiping edge of the squeegee as it is moved across the stencil.

The wiping action of the squeegee is effected by rotation of the manipulating knob at the opposite end of the shaft 64. As previously stated, the rotation of the knob is limited by the limit pins and the stop pin on the knob. As the knob is rotated, the motion is transmitted to the bell crank by means of the bifurcated block to which the bell crank is attached. The operating shaft for the squeegee is on the same center as the cylindrical object being stenciled. Consequently, the squeegee moves in an arc of the same radius as the interior surface of the object being stenciled.

Having described my invention, I claim:

1. A stenciling apparatus comprising, a chuck for supporting hollow ware and a stenciling unit 30 adjustably mounted for insertion into said hollow ware, said stenciling unit including a screen, a squeegee, and means for operating the squeegee relative to the screen.

2. A stenciling apparatus comprising, a chuck 35 for supporting hollow ware such as a cup, a stenciling unit, means adjustably supporting said chuck and stenciling unit independently of each other for axial alignment, said stenciling unit incorporating an axially shiftable stencil screen 40 having a curvature fitting the interior of the hollow ware, and a squeegee carried by said axially movable element, and means for moving the squeegee against the screen and for rotating the squeegee for decorating the interior of the hollow 45 ware.

3. A stenciling apparatus comprising, means for supporting hollow ware such as a cup, stenciling means, said stenciling means incorporating a stencil screen having a curvature fitting the interior of the hollow ware, and means carried 50 by said stenciling means for printing through said screen for decorating the interior of the hollow ware.

4. A stenciling apparatus comprising, means 55 for supporting hollow ware, a stenciling unit insertable in said hollow ware, said stenciling unit incorporating a movable member carrying a stencil screen and a squeegee whereby the stencil screen and the squeegee may be inserted in the hollow ware and decoration applied to the interior thereof.

5. Apparatus for stenciling concave surfaces, comprising, means for supporting an object having a concave surface, a stenciling unit adapted 65 to be moved into position adjacent said concave surface, said stenciling unit incorporating an arcuate stencil screen having a curvature fitting the concave surface, and a squeegee movable across the screen for decorating the concave surface.

6. A stenciling apparatus comprising, means 70 for supporting hollow ware, a stenciling unit adjustably mounted for insertion into said hollow ware, means for holding the unit in position in the hollow ware, said stenciling unit including 75 a screen, a squeegee, and means independent of

the first holding means for operating the squeegee relative to the screen.

7. A stenciling apparatus comprising, a chuck for supporting hollow ware, a stenciling apparatus 5 consisting of a tubular support, means for supporting said tubular support in alignment with the axis of the hollow ware, and a stencil screen, said screen supported on said tubular support, means for moving the tubular support axially for moving said screen into the hollow ware, a shaft 10 extending through said tubular support and rotatably and translatable mounted therein, said shaft carrying a squeegee adjacent to said stencil screen, means for moving said squeegee into contact with the stencil screen and for rotating the 15 same for decorating the interior of the hollow ware.

8. A stenciling apparatus comprising, a base, a chuck mounted on said base, a stenciling unit 20 mounted on said base, said chuck and stenciling unit adjustable with respect to each other for alignment thereof, and said chuck adapted to support hollow ware with the opening of the hollow ware disposed toward the stenciling unit, whereby said stenciling unit may be inserted in 25 the hollow ware and decoration applied to the interior thereof.

9. A stenciling apparatus comprising, a base, standards mounted on said base for adjustment toward and from each other, a chuck pivotally 30 mounted on one of said standards, a stenciling unit pivotally mounted on the other of said standards, the axes of said stenciling unit and said chuck alignable by movement on the pivots, said chuck adapted to support hollow ware with the 35 opening of the hollow ware disposed toward the stenciling unit, and said stenciling unit incorporating an axially movable member carrying a stencil screen and a squeegee, whereby the stencil screen and the squeegee may be inserted in the 40 hollow ware and decoration applied to the interior thereof.

10. Stenciling apparatus comprising, support means, including a cradle for receiving and supporting hollow ware in fixed position, stenciling 45 means adjustably mounted for insertion in said hollow ware and operable for decorating the interior thereof, and means adjustably supporting said support means and stenciling means for varying the spacing of these means.

11. A stenciling apparatus comprising, means for supporting hollow ware, a tubular support, means for supporting said tubular support in alignment with the axis of the hollow ware, a 55 stencil screen, said screen mounted on said tube, means for moving the tubular support axially, a shaft extending through said tubular support rotatably and translatable mounted therein, said shaft pivotally carrying a squeegee at one end adjacent to said stencil screen, means for 60 rocking said squeegee into contact with the stencil screen by translation of said shaft, for rotating the same to decorate the interior of hollow ware.

12. A stenciling apparatus comprising, a base, standards longitudinally adjustably mounted on 65 the base, a chuck mounted on one standard and projecting toward the other, a stenciling unit on the other standard including a tubular support carrying a stencil screen and adapted to be axially aligned with hollow ware supported in the 70 chuck, said stencil screen of arcuate form for fitting the interior of the hollow ware an axially and rotatably mounted shaft in said tubular support, a squeegee pivotally mounted on the inner end of said shaft, a spring for normally maintain- 75

ing said squeegee out of engagement with the stencil screen, said squeegee including means in contact with the tubular support whereby upon movement of the shaft away from the chuck, the squeegee is moved into contact with the stencil screen, and upon rotation displaces the paint through the screen for decorating the interior surface of the hollow ware.

13. A stenciling apparatus comprising, a chuck, a tubular support carrying a stencil screen and adapted to be axially aligned with hollow ware supported in the chuck, said stencil screen fitting the interior of the hollow ware, an axially and rotatably mounted shaft in said tubular support, a squeegee pivotally mounted on the inner end of said shaft, means for normally maintaining said squeegee out of engagement with the stencil

screen, said squeegee including means in contact with the tubular support whereby upon movement of the shaft away from the chuck the squeegee is moved into contact with the stencil screen and upon rotation displaces the paint through the screen for decorating the interior surface of the hollow ware

14. In an apparatus for interiorly decorating hollow ware, a holder for the hollow ware, a stencil decoration applicator unitarily constituting a relatively movable screen for the transfer of the decoration to the interior surface of the hollow ware, and a squeegee to effect the transfer, said holder and applicator movable relatively for insertion of the screen and squeegee within the hollow ware.

JOHN C. SMITH.
